UNITED STATES PATENT OFFICE.

EMIL HOENIG, OF NEW YORK, N. Y.

DESIGN FOR A STATUETTE, SCULPTURE, OR ARTICLE OF SIMILAR NATURE.

57,651.

Specification for Design.

Patented Apr. 26, 1921.

Application filed October 29, 1920. Serial No. 420,575. Term of patent 3½ years.

To all whom it may concern:

Be it known that I, EMIL HOENIG, a citizen of the United States, residing at New York, in the county of Kings and State of New York, have invented a new, original, and ornamental Design for a Statuette, Sculpture, or Article of Similar Nature, of which the following is a specification, reference being had to the accompanying drawings, forming part thereof.

I claim:

The ornamental design for a statuette, sculpture, or article of similar nature, as shown.

EMIL HOENIG.
